UNITED STATES PATENT OFFICE

126,606

DESIGN FOR A RADIO-PHONOGRAPH
CABINET

Edgar F. Haines, Philadelphia, Pa., assignor to
Philco Radio and Television Corporation,
Philadelphia, Pa., a corporation of Delaware

Application January 23, 1941, Serial No. 98,337

Term of patent 14 years

To all whom it may concern:

Be it known that I, Edgar F. Haines, a citizen of the United States, residing in Philadelphia, Philadelphia County, Pennsylvania, have invented a new, original, and ornamental Design for a Radio-Phonograph Cabinet, of which the following is a specification, reference being had to the accompanying drawings, forming part thereof, in which:

Fig. 1 is a front perspective view of a radio-phonograph cabinet showing my design; and

Fig. 2 is a front perspective view thereof with the record playing unit as it appears in the forwardly tilted or open position.

The characteristic feature of the present design resides in the appearance of the cabinet when the front panel or grille thereof is in open position as best shown in Fig. 2.

I claim:

The ornamental design for a radio-phonograph cabinet, substantially as shown and described.

EDGAR F. HAINES.
